CLAIM

The ornamental design for a terrier arm puppet, as shown and described.

DESCRIPTION

FIG. 1 is a front view of the terrier arm puppet showing my new design;

FIG. 2 is a front view on a larger scale than FIG. 1 of the head of the terrier arm puppet;

FIG. 3 is a view from the side and front and on a larger scale than FIG. 1 of the head of the terrier arm puppet;

FIG. 4 is a back view of the terrier arm puppet;

FIG. 5 is a top view of the terrier arm puppet;

FIG. 6 is a left side view of the terrier arm puppet, the right side being a mirror image thereof; and,

FIG. 7 is a bottom view of the terrier arm puppet.
